CLAIM

The ornamental design for a coffee capsule, as shown and described.

DESCRIPTION

FIG. 1 is a top perspective view of a coffee capsule showing our new design;

FIG. 2 is a front view thereof;

FIG. 3 is a rear view thereof;

FIG. 4 is a left side view thereof;

FIG. 5 is a top view thereof;

FIG. 6 is a bottom view thereof; and,

FIG. 7 is a bottom perspective view thereof.

The stippling effect in the FIGS. 1 through 5 and 7 depicts a contrast in appearance. In FIGS. 5 through 7 the broken lines illustrate unclaimed subject matter only and form no part of the claimed design.
